UNITED STATES PATENT OFFICE.

BENJAMIN K. REED AND BARTLEY L. BURRIS, OF WICHITA, KANSAS.

EXCAVATOR.

SPECIFICATION forming part of Letters Patent No. 322,319, dated July 14, 1885.

Application filed June 9, 1884. (No model.)

To all whom it may concern:

Be it known that we, BENJAMIN K. REED and BARTLEY L. BURRIS, of Wichita, in the county of Sedgwick and State of Kansas, 5 have invented a new and useful Improvement in Excavators; and we do hereby declare that the following is a full, clear, and exact description of the same.

Our invention relates to excavators of that 10 class in which the earth is carried up and discharged by means of endless belts or conveyers.

In the accompanying drawings, Figure 1 is a side elevation, and Fig. 2 is a plan view, 15 of the apparatus. Fig. 3 is a transverse section through the carrying-wheels. Fig. 4 shows in detail the mechanism for driving the transverse conveyer.

A main frame, A, is supported on wheels 20 b b and B B', and carries the working parts. The wheels B B' are loose on an axle, C, and each has a circular rack, c, interval teeth. On the frame is journaled a shaft, d, with a pinion, 7, meshing into the internal gear of 25 wheel B. A larger pinion, D, on the same shaft meshes with a pinion, E, on counter-shaft e. The timbers F F of the frame on which the shafts d and e are journaled run longitudinally, and one is by the side of the 30 opening left for the main elevator. On the shaft e is a sprocket-wheel, G, connected by a chain, f, to a sprocket-wheel, g, on the shaft of the upper roller of the main elevator. This elevator may, therefore, be adjusted 35 by raising or lowering its upper end without deranging the gearing.

The internal gear on wheel B' is in mesh 40 with a pinion, H, on shaft h, journaled in a short beam, K, the forward end of which is supported on the axle. On the inner end 45 of the shaft h is a bevel-gear, k, in mesh with a little gear, l, on a shaft, L, journaled in the frame. On the outer end of this is a sprocket-wheel, L', which is connected by a chain to a like wheel, l', on the end of the 50 roller-shaft of the lateral conveyer or elevator N, this allowing, also, vertical adjustment of the outer end of the conveyer N. Thus the two conveyers M and N are driven independently.

The plow O is formed with a landside, point-share, and low, slightly-inclined mold-board, the rear end of which is substantially at right angles to the landside, and termi-

nates just over the front end of the main conveyer. The plow is connected to the beam by standards p q and cutter r, both of thin iron. The beam is connected at the rear end to the frame by links 1 and 2, so that it may swing freely in vertical plane. The front end is connected to the pivoted draw bar or link, which has a vertical conveyer-arm, Q, on the rear end. This link is pivoted in a hanger, t, on the frame, and the arm Q is provided with rack-teeth, into which meshes a segment, 3, pivoted between two plates or standards, 4 4, on the frame. The arm Q also passes between these standards, and is thus held constantly in gear with the segment. A spring handle or lever, 5, fixed to the segment, moves past and engages with a curved rack, 6, by means of which the plow can be set at any desired depth, and by reason of the manner of suspending the plow always maintains approximately the same level.

The forward wheels are mounted on a short axle, with ordinary fifth-wheel connection with the frame. The axle allows the wheel to turn by the side of the plow-connections quite around to right or left, and the whole machine may thus be turned in very small space. The plow cuts behind these wheels, and the low and slightly-inclined mold-board conveys the earth back to the conveyers, which are of ordinary construction, and carry the earth up and discharge it in the usual manner.

As the wheels are independent, and one connected to the main and the other to the lateral conveyer, they may turn in opposite directions at the same time, and this, with the mode of arranging the forward wheels, renders the turning practicable.

We claim as our invention—

The plow with its beam suspended in the rear from links, and with its front end attached to a pivoted draw-bar provided with rack-arms and segment, the mold-board extending back to and connected with the main elevator, substantially as described.

In testimony whereof we have signed our names to this specification in the presence of two subscribing witnesses.

BENJAMIN K. REED.
BARTLEY L. BURRIS.
